COUPLED AMPLIFIER CASCADE

Edwin Severin, Berlin-Tempelhof, Germany, assignor to Telefunken Gesellschaft fur Drahtlose Telegraphie m. b. H., Berlin, Germany, a corporation of Germany

Application February 4, 1938, Serial No. 188,699
In Germany February 6, 1937

2 Claims. (Cl. 179—171)

An object of this invention is the reduction of the rattle or blur factor (non-linear harmonic distortion) in case of grid modulation and reduction in size of modulator tubes. The object is attained as follows:

In the presence of the radio frequency carrier the grid-current characteristic as a function of the audio frequency potential follows roughly a square law. The plate-current characteristic of the modulator tube presents a similar shape. Both may be made to coincide or register optionally by the aid of parallel or series resistances. The invention has been tried out in the laboratory and it has been embodied in various instances in practice.

The invention is concerned with an amplifier cascade in which an input tube controls a tube connected to its output which latter tube, subject to the influence of the driver or control currents, operates in the presence of fluctuating grid cathode impedance. The invention more particularly is concerned with modulation circuit organizations in which, by the aid of a transformer, the grid circuit of a mixer tube wherein modulation takes place is driven from a modulation amplifier tube, referred to herein-after as a modulator tube. The end or power stage of a modulation amplifier, particularly in the case of grid voltage modulation, is loaded by a consumer or load device, that is, the mixer tube whose resistance is a function of the amplitude of the driving voltage and which is roughly of a shape following a square law. This shape is due to the grid-current characteristic of the mixer tube.

Mixer tubes of this kind have in the past been operated in such a manner that the size of the tubes was chosen as ample as possible, while their internal impedance was chosen low in order that the lack of linearity of the aggregate circuit may turn out as small as feasible, so that, in spite of a variable external resistance, the voltage at the non-linear consumer or load may be practically sinusoidal in form. To this end, however, very large mixer tubes have been required, and the result has been that equipment of this kind turned out to be expensive and uneconomical in use, thereby precluding its employment in transportable or portable equipment. The attempt to use smaller mixer tubes, however, is defeated by inadmissibly high blur or rattle factor (non-linear harmonic distortion).

Now, the solution disclosed in the invention is predicated upon the fact that the grid-current characteristic of the mixer tube 2 and the plate

current characteristic of the modulator tube obey the same emission laws. This very fact offers ways and means designed to combat and cure the above distortion effect. Thus, according to the invention the internal impedance of the modulator tube is adapted as far as feasible to the grid-cathode resistance of the tube 2 which represents the consumer or load insofar as the working voltages and the working point of the modulator tube are so chosen that for each point of the operating characteristic the inner resistance of the modulator tube is entirely or nearly equal to the transferred outer resistance resulting from the transformer-coupling of the grid-cathode path of the tube 2. Such adaptation or matching which will preclude distortions results, in the majority of cases, without the use of distinct auxiliary means. Under certain circumstances it may be necessary, by the use of suitable series or parallel impedances, provided in the plate circuit and/or the load circuit to secure matching between the outside circuit and the inner circuit of the tube. My invention is, of course, not limited to cascaded stages transformer-coupled but is applicable to any relaying stages connected in cascade by circuits which transfer variations in impedance from one stage to the preceding stage or vice versa.

An exemplified embodiment of the invention is represented in Figure 1 of the drawing. Figures 2 and 3 are curves used in describing the operation of my invention.

Referring to the drawing, 1 denotes the modulator tube controlled by the voice currents and which through a transformer T₁, acts upon the grid circuit of the mixer tube 2. The introduction of the radio frequency in the grid circuit of the tube 2 is insured by the aid of a transformer T₂. In parallel relation to transformer T₁ a by-pass condenser C is provided for the radio frequency. The requisite grid biasing voltage is furnished from the battery B. The modulation transformer T₁ is so designed that the two characteristics R₁ and R₂ as a function of e_a will practically come to register. The curve R₁ represents the internal resistance of the modulator tube 1 for the load curve R₂ which is the grid to cathode resistance of the modulated tube 2.

Figure 2 shows the grid-current characteristic of the tube 2. The abscissa stands for the grid potential e_g, and the ordinate for the grid current i_g, and for the resistance R₂ of the grid-cathode path which is a function of the grid voltage and the grid current. The graph denoted by i_g illustrates the inter-dependence between the grid

current and the grid biasing potential; while graph R_a shows the dependence of the resistance of the grid-cathode path of the tube to be modulated

$$R_a = \frac{de_a}{di_a}$$

upon the grid biasing potential.

As the grid of tube 1 is swung more negative by the modulation voltage the internal resistance R_i (the ratio of an increment of plate voltage to the resulting increment of plate current) increases, and vice versa, as is well known. Now transformer T_1 is so poled that the grid of tube 2 also swings more negative as the grid of tube 1 becomes more negative so that R_a also increases, as shown by Fig. 2. In other words, modulation potentials applied to the grid of tube 1 cause both R_i and R_a to vary similarly. This is shown in Figure 3. The dash-line curve corresponds to the shape of R_a , the solid-line characteristic corresponds to the shape of R_i . What may be seen from this diagram is that the two resistances roughly have the same form which proves that the occurrence of non-linear distortions has been reduced to a minimum amount. This is because the amplification depends on the ratio of load resistance R_a to internal tube resistance R_i so that the amplification will not vary with input amplitude (i. e. there will be no non-linear distortion) if the ratio R_a/R_i is maintained independent of input amplitude.

The matching impedances used in some cases are shown in shunt to the windings of T_2 of Figure 1.

I claim:

1. In a linear modulation system, an electron discharge tube device having grid and cathode electrodes coupled with a source of carrier wave energy to be modulated, a source of modulating potentials, an electron discharge amplifier tube having input electrodes coupled to said source of

modulating potentials, said electron discharge amplifier tube having output electrodes, a modulation potential transformer having a primary winding connected to the output electrodes of 5 said electron discharge amplifier tube and having a secondary winding connected to the grid and cathode of said first named tube, the transformer coupling being so arranged that the internal resistance characteristic of the said amplifier increases when the load impedance impressed by the grid to cathode circuit of said first named tube increases and vice versa to thereby maintain a constant relation between the voltage across the said grid circuit comprising the 10 non-linear load and the modulating potential impressed on the input electrodes of the electron discharge tube amplifier.

2. In a modulation system, a first tube having a grid and cathode connected in a grid cathode circuit excited by wave energy to be modulated, and having modulating potentials impressed on said grid circuit, wherein the ratio of grid current averaged over a radio-frequency cycle to modulation potential impressed increases with 15 increasingly positive modulation potential, a second tube having a grid electrode excited by modulation potentials and having an anode coupled to said grid circuit of said first tube for impressing said modulation potential on the said grid circuit of said first tube, means for causing the ratio of anode current of said second tube to grid potential of said second tube to increase with increasingly positive modulation potential 20 on the grid of said second tube, and a transformer in said coupling between the anode electrode of said second tube and said grid circuit of said first tube, the polarity of said transformer being so chosen as to make both of said ratios increase with increasingly positive modulation potential on the grid of said second tube.

EDWIN SEVERIN.
